UNITED STATES PATENT OFFICE.

ZERAH L. HAYDEN, OF CEDAR RAPIDS, IOWA.

VAGINAL SYRINGE.

SPECIFICATION forming part of Letters Patent No. 609,432, dated August 23, 1898.

Application filed February 15, 1898. Serial No. 670,345. (No model.)

To all whom it may concern:

Be it known that I, ZERAH L. HAYDEN, a citizen of the United States, residing at Cedar Rapids, in the county of Linn and State of Iowa, have invented certain new and useful Improvements in Vaginal Syringes; and I do hereby declare the following to be a full, clear, and exact description of the invention, such as will enable others skilled in the art to which it appertains to make and use the same.

This invention relates to instruments for the treatment of the female organs of generation, and has for its object to provide efficient means for irrigating or medicating the uterus and adjacent parts and drawing out therefrom diseased or deleterious matter.

The invention consists, essentially, in a pump provided with a vent-pipe to regulate its suction and injecting apparatus for medicating or irrigating purposes.

In the accompanying drawings, forming a part of this specification, Figure 1 is a side elevation of a device embodying my invention, a portion of the upper end of the main cylinder being broken away to show the outlet. Fig. 2 is a central section of the same and in the same plane.

Similar letters of reference indicate corresponding parts.

In many cases of disease peculiar to women it is desirable to thoroughly cleanse the uterus and adjacent parts, as by the administration of a douche or the like. This invention is designed to accomplish the same purpose by means less cumbersome than those in common use and better calculated to force or draw out injurious matter from the parts affected.

Referring to the drawings, A denotes the cylinder of a small pump of suitable size for the vagina. This is provided with a piston B, the rod B' of which is provided with a suitable lifting-head B². The piston does not differ essentially from that of an ordinary pump and is provided with a check-valve B³, arranged as in the ordinary lift-pump.

At the lower end the cylinder is provided with a suitably-rounded nozzle C, provided 50 with a check-valve C' and perforated, as shown.

At the upper end of the cylinder, or near

it, is an outlet nozzle or nipple A', adapted to connect with a bulb D to receive whatever may be drawn out.

Along one side of the cylinder A and permanently attached thereto is a vent-pipe E, communicating at the lower end with the perforated nozzle C and at the upper end provided with a shallow cup E' to receive the finger of the operator. By this means the suction of the piston may be regulated, the operator closing or unclosing the vent according as the suction of the pump may be painful or otherwise. On the opposite side of the cylinder is a small pipe F, open at both ends, the lower end communicating also with the nozzle C and the upper end curved away from the cylinder-head A² and adapted for the attachment of a short piece of rubber tube G, to which is connected a bulb H. The communication of either the vent-pipe or this pipe with the nozzle need not be wholly internal, as indicated in Fig. 2, since practically the same results are secured by an opening at the lower end of either pipe adjacent to the nozzle.

In the operation of the device the bulb H is first filled with water or with any suitable liquid medicinal preparation with which to irrigate the affected parts. The pump being then inserted in the vagina the liquid in the bulb is injected and after having produced the desired beneficial effects is drawn out by means of the pump into the bulb D to be discharged on the removal and cleansing of the pump.

Having thus described my invention, what I claim as new, and desire to secure by Letters Patent, is—

1. The combination in a vaginal syringe, of a pump, composed of a cylinder with an outlet near the upper end, a suitable cylinder-head through which the piston-rod passes, a piston-rod having a lifter at the outer end and a valved piston at the other end, and a perforated nozzle at the lower end of the cylinder, with a valve therein, and a vent-pipe attached to said cylinder, its open, lower end communicating meditately or directly with said nozzle, and its open upper end having a suitable finger-cup, substantially as described.

2. The combination with a pump, substan-

- tially as described, consisting essentially of a cylinder with a valved, perforated nozzle at the lower end, an outlet near the upper end, a head to receive the piston-rod, and a suitable valved piston, rod and lifter, of an open-ended pipe attached to one side of the cylinder, its lower end communicating with said nozzle, and means substantially as described for injecting liquid through said pipe.
- 10 3. The combination of a pump substantially as described, provided with vent and injec-

tion pipes and a suitable discharge-outlet, and the receiving and injecting bulbs removably attached to said outlet and injecting pipes, respectively.

15 In testimony whereof I affix my signature in presence of two witnesses.

ZERAH L. HAYDEN.
